UNITED STATES PATENT OFFICE.

ASBURY REED, OF LOS ANGELES, CALIFORNIA, ASSIGNOR TO UNITED STATES REAMER AND TOOL CORPORATION, OF LOS ANGELES, CALIFORNIA, A CORPORATION OF CALIFORNIA.

REAMER AND BURNISHING TOOL.

Application filed October 8, 1923. Serial No. 667,304.

This invention relates to a reamer and burnishing tool.

- An object is to provide a tool including a guide in the form of a sleeve consisting of 5 a number of longitudinal, independent and separable pieces, and which form a support for the work and tool and is capable of expansion and contraction to fit a bore to be scraped or reamed and burnished.
- 10 An object is to provide a burnishing and scraping tool that will operate to effectively, quickly and accurately work to a fineness of one-half of one-thousandths (.0005) of an inch, more or less, and which will operate 15 to burnish to a mirror finish.

A further object is to provide a scraping or cutting and burnishing tool including a sectional or segmental shell, sleeve or shroud or burnishing jacket that is capable 20 of being adjusted so as to form a substantially cylindrical, peripheral surface that may snugly bear and rub upon the surface to be treated, and an object, in this connection, is to provide a shell, sleeve or 25 jacket in which the sections are relatively separate from each other so that they can be removed from a central mandrel readily, without necessitating an endwise or longitudinal shifting of the sleeve or shell from 30 the mandrel.

Another object is to provide a burnishing and scraping reamer including a sleeve or shell formed of sections which are independently removable and which may be 35 currently expanded while maintaining a cylindrical, peripheral form while they are mounted on the mandrel; in this connection a further object is to provide a burnishing and scraping reamer including an effective 40 cutting or scraping means which is adjustable independently of the burnishing means upon the mandrel.

Other objects and advantages will be 45 made manifest in the following specification of embodiments of the invention illustrated in the accompanying drawings, wherein:

Figure 1 is a side elevation of a form of the tool.

Fig. 2 is a central, longitudinal section 50 of the same.

Fig. 3 is a perspective of the mandrel of Figure 1.

Fig. 4 is a perspective of one of the sleeve segments.

Fig. 5 is a perspective of a portion of 55 a mandrel having flat expansion faces for shell or sleeve segments.

Fig. 6 shows a fragment of a modified form of shell segment.

In Figures 1 to 4 inclusive there is illustrated a scraping and polishing reamer which includes a central mandrel having a longitudinally tapering body 2, one end of which is flattened as at 3 to provide for effective holding of the tool when in operation. One end of the mandrel is provided with threads 4 of a suitable pitch to receive the clamping ring 4^a, and the opposite end is provided with a threaded portion 5 receiving a clamping collar 6 and receiving 70 coordinate clamping collars 7 and 8. The mandrel 2 is provided along one side with a longitudinally extending channel or slot 9, and in this there is mounted for longitudinal movement a scraper or cutting blade 75 10, having one inclined edge 10^a complementary to the inclined bottom of the slot 9. The outer, effective edge 10^b of the cutter blade is designed to remain parallel with the axis of the mandrel as the cutter blade may be shifted in either direction along the slot 9 in the mandrel. To effect this shifting the cutter blade is provided with an outwardly extending lug 10^c disposed between the respective clamping 80 rings 7 and 8 threaded on the shaft 5 of the mandrel. It will be seen that the two rings 7 and 8 serve to shift and to lock the cutter 10 in the desired position; sliding the cutter 10 in one direction, as up the inclined bottom of the slot 9, shifts the cutter 10 outwardly, while movement in the opposite direction enables the cutter to be shifted inwardly.

An important feature of this invention 95 includes means forming a shell, shroud or jacket made up of independent sections 11 which are adapted to be assembled around and upon the mandrel 2 and securely clamped in position with their outer faces in a common circle and therefore forming a cylinder. The sections 11 are tapered in thickness and have their inner faces conically concaved. The outer faces of the sec-

tions 11 are cylindrically convex. These independent sections are adapted to be expanded or contracted on the mandrel to a degree of extreme accuracy for burnishing and reaming purposes.

In Figure 3 the mandrel 2 is shown as of conical form and in such case in the inner faces of the sections or segments 11 will be concave, as at 11^a. The segments are of 10 substantially oblong form in plan as shown in Figure 1, and have bevelled, convergent ends 11^b presented to complementary bevelled end faces of the clamp rings 4^a and 6 so that the several segments 11, when assembled upon the tapering mandrel 2 may be uniformly adjusted longitudinally on the mandrel and then firmly clamped in a position according to the desired effective diameter of the cylinder formed by the sleeve or 15 jacket consisting of the segments or sections 11.

Any suitable means may be employed to hold the segments 11 against undue lateral play, and such means may consist of rigid side, guide, longitudinally extending shoulders 2^b formed or provided on the tapering body of the mandrel 2 and between or against which shoulders the side edges of the sleeve segments may rest.

30 A simple and practical form of mandrel is shown in Figure 5 in which the tapering body, instead of being conical, is substantially in the form of a frustum of a pyramid. That is, the tapered body is provided with 35 any suitable number of longitudinal flat faces 2^c upon which may bear contiguous flat faces of segments otherwise of the type shown in Figure 4. This form of construction is very desirable for the reason that 40 when the segments 11 have inner flat faces they will be supported upon the opposed flat faces 2^c of the pyramidal reamer body. The sections or segments 11 applied on the pyramidal reamer body may be retained against 45 lateral movement in any suitable manner as for instance by the longitudinal edges 2^d of longitudinal recesses 2^e which may be formed in the flat faces of the body; the edges 2^d being engaged by complementary shoulders 11^c of the segments extending 50 along the inner faces of the segments 11, Figure 6.

The sectional sleeve, shell or shroud, forms 55 essentially an expandable guide which, in its sufficiently contracted position, can be entered into the bore hole of whatever part it may be intended to ream and burnish and then the sleeve is sufficiently expanded to 60 slightly circumferentially bear upon and rub against the surface of the bore so that when the tool and the work are relatively rotated, the one steadies and supports the other and therefore entirely prevents any relative vibration. After the guide and support, consisting of the sectional, expanding sleeve has

been snugly fitted to the desired degree of friction and resistance, the cutter is then expanded to a position so as to be effective to scrape or cut the surface of the bore when the work and the tool are relatively rotated. 70 It will be seen that the snug fit of the guide-forming, expandable, sectional sleeve or shell forms a firm carrying means for the tool and chatter of the tool and work is entirely overcome. 75

After an initial scraping or cutting operation has been completed to the desired degree, then the expandable guide is again adjusted to increase its effective diameter and thus take up the play and can be made to bear and rub upon the bore surface. This mode of operation or successive adjustment of guide shell and cutter is repeated until the desired finished dimension is obtained, and then the cutter may be sufficiently retracted to permit the rotation of the guide shell while it is bearing snugly on the bore surface to effect an ultimate high burnish or polish of the surface.

Further embodiments, modifications and 80 variations may be resorted to within the principle of the invention.

What is claimed is:

1. In a burnishing and scraping reamer, a mandrel, longitudinal scraping means adjustably mounted on the mandrel for expansion and retraction, a shell mounted on said mandrel and consisting of independently applicable and removable, longitudinally extending segments having curved, outer, effective burnishing faces, and means for securing the sectional shell in various positions of adjustment along the mandrel. 95

2. A scraping and burnishing reamer including a mandrel having a tapered body portion, a sleeve including a plurality of segments and being longitudinally adjustable along said tapered body portion whereby to be expanded or retracted, means for clamping the shell segments in a desired position along the tapered body portion, a longitudinally extending, adjustable cutter member mounted upon the reamer body and being adapted to project beyond the mounted shell, and means for securing the cutter member in adjusted position; the shell segments having convergently bevelled end faces and said clamping means including rings with end faces bevelled complementary to the end faces of the shell sections whereby to hold the segments in position. 105 110 115

3. A scraping and burnishing reamer comprising a mandrel, a shell formed of a plurality of independent segments mounted upon said mandrel, means for expanding or contracting said shell upon said mandrel, a cutter adjustably mounted upon said mandrel adapted to be projected outwardly from said shell, and means for adjusting said cutter independently of said shell. 120 125 130

4. A scraping and burnishing reamer comprising a tapered mandrel, a shell formed of a plurality of independent segments longitudinally slidable upon said mandrel, clamping collars for holding said segments upon said mandrel in longitudinally adjusted position thereon, a cutter adapted to be projected outwardly from said shell, and means for adjusting said cutter independently of said shell. 25
5. A scraping and burnishing reamer comprising a mandrel, a shell formed of a plurality of independent segments mounted upon said mandrel, means for expanding or contracting said shell upon said mandrel, a cutter adjustably mounted upon said mandrel adapted to be projected outwardly from said shell, and means for adjusting said cutter independently of said shell, there being portions projecting from said mandrel between said segments for preventing rotary movement of said segments upon said mandrel. 30
- 10 15 20
6. A scraping and burnishing reamer comprising a tapered mandrel, a shell formed of a plurality of independent segments longitudinally slidable upon said mandrel, collars longitudinally adjustable upon said mandrel for forcing said segments in either direction thereon thereby causing the expansion or contraction of said shell, and a cutter independently adjustable upon said mandrel adapted to be projected outwardly from said shell or to be withdrawn therewithin. 35
7. A scraping and burnishing reamer comprising a mandrel, an expandable shell mounted upon said mandrel, an inclined groove formed in said mandrel, a cutter slideable in said groove adapted to be projected outwardly from within said shell, said cutter having an outwardly turned extension, and collars longitudinally adjustable upon said mandrel engaging the opposite sides of said extension for sliding said cutter independently of the shell and holding said cutter in adjusted position. 40 45
